UNITED STATES PATENT OFFICE.

CHARLES H. CHAMBERLAIN AND CARL E. BEST, OF KANSAS CITY, MISSOURI.

ADVERTISING DEVICE.

1,236,907.

Specification of Letters Patent.

Patented Aug. 14, 1917.

Application filed August 14, 1916. Serial No. 114,896.

To all whom it may concern:

Be it known that we, CHARLES H. CHAMBERLAIN and CARL E. BEST, citizens of the United States, residing at Kansas City, in the county of Jackson and State of Missouri, have invented certain new and useful Improvements in Advertising Devices; and we do declare the following to be a full, clear, and exact description of the invention, such as will enable others skilled in the art to which it appertains to make and use the same.

This invention relates to useful improvements in advertising devices, and the principal object of the invention is to provide an advertising device in which the advertiser may display the desired information in a card holder, which is opened for the insertion of the card upon depositing a coin in the device.

Another object of this invention is to provide an advertising device of this character, which is adapted after the device has been opened, the card placed within, and the same again securely locked, to eject the card from the holder, without it being necessary to reopen the same.

Another object of this invention is to provide a device of this character, which is easily and simply constructed, inexpensive to manufacture, and one which will be very efficient in operation.

With these and numerous other objects in view, our invention consists of the certain novel features of construction, combination and arrangement of parts, which will be herein referred to and more particularly pointed out in the specification and claims.

40 In the accompanying drawings:

Figure 1 is a front elevation of a device constructed in accordance with this invention;

Fig. 2 is a rear elevation of the same in an inverted position and showing the parts in their locked positions;

Fig. 3 is a top plan view of the device, the card holding device being in its closed position;

50 Fig. 4 is a rear elevation of the device, inverted and showing the movable parts of the same in their unlocked or released positions;

Fig. 5 is a top plan view of the device, showing the card holder in its opened position;

Fig. 6 is a transverse sectional view taken on the line 6—6 of Fig. 2;

Fig. 7 is a similar view taken on the line 7—7 of Fig. 5;

60 Figs. 8 and 9 are transverse sectional views taken on the lines 8—8 and 9—9 of Fig. 2;

Fig. 10 is a perspective view of the card holder detached from the remaining parts 65 of the device; and

Fig. 11 is a similar view of the lock applied detached from the other parts of the device.

In describing our invention, we shall refer 70 to the drawings, in which similar reference characters designate corresponding parts throughout the several views, and in which we have illustrated one of the devices, although when desired, a plurality of them 75 may be used, the same being positioned within a frame, in a wall or any other convenient place. This advertising device is designed to cover the wants of commercial men and others that desire to be placed in 80 touch with prospective buyers, where personal solicitation cannot be had. The device is designed primarily for use in hotels and other public places, where the use of a personal card carrying the room number, or 85 other information, and line of merchandise can be displayed publicly for commercial purposes.

The numeral 1 designates a support, 90 which may be formed of any desired material, and which has hinged to the front of the same a card holding device 2. This card holding device consists of a substantially rectangular frame 3 with laterally extending flanges 4, the side edges of which 95 are provided with rearward extensions 5, which are adapted to slide through slots 6 in the support. Within the flanges 4 of the card holder may be placed glass or any other transparent material, so that any card 100 placed within this holder may be easily observed, and yet will be securely locked therein.

The card holder 2 is hinged to the support 1 as shown at 7, and the rearwardly extending sides 5 of the the same that project through the support are provided at their upper edges with upwardly extending stops 7' which limit the forward movement of the holder. These sides 5 have also apertures 110 8 extending therethrough adjacent the upper edges, and the front portion of the

same, for a purpose to be hereinafter fully described.

Projecting from the inner side of the support 1 intermediate the side extensions 5 of the card holder is a stud 9 which is adapted to have secured thereon one end of a pair of coil springs 10. These coil springs have their opposite ends secured to the side extensions 5 of the card holder adjacent the outer ends of the same, and it will be obvious that when the front face of the card holder which is disposed at the other side of the support is positioned against the same, the coil springs 10 will be placed under tension and hence they will exert a constant outward pull on the holder, so that upon releasing the same, it will be immediately thrown forward. The forward movement of the card holder is limited by the stops 7' on the upper edges of the same. These springs will always tend to move the card holder forward as soon as the same is released, so that when this takes place, the same will be opened, and a card may be readily inserted therein.

We have provided means for locking the card holder in position against the outer face of the support, which comprises a lock plate 11, which is slidably mounted against the inner surface of the support. This lock plate is provided at its lower edge with a pair of notches 12, which have projecting from one side of the same and extending in the same direction, lugs 13. Positioned within the notches 12 are substantially T-shaped guides 14, which slidably support the locking plate in position, and said plate is additionally secured in position by a bracket 15 secured adjacent one end as clearly shown in Fig. 2 of the drawings. This lock plate is provided adjacent the bracket 15 with an outwardly stamped portion 16 with spaced sides to form a coin chute for a purpose to be hereinafter more fully described. The lower end of the coin chute 16 is notched as shown at 17, and in position directly beneath the same is a projecting stop 18 which is adapted to hold the coin in the lower portion of the chute until the device is operated.

A coil spring 19 has one of its ends secured to one of the T-shaped guide studs 14, while its opposite end is secured to the plate as shown at 20. This coil spring 19 will exert a constant pull on the plate, and will tend to move the same in the direction of the lugs 13. When the card holder 2 is moved up against the outer face of the support 1, the alining apertures 8 therein will be positioned directly behind the support, and they will come into alinement with the lugs 13 of the locking plate 11. Owing to the fact that the locking plate is under the constant action of spring tension, the lugs 65 will be projected through the openings, and

consequently the card holder will be locked in position. The upper edges of the side extensions 5 of the card holder will swing through the notches 12 in the lower edge of the locking plate.

When in the above described position, the card holder will be securely locked against the outer face of the support, and we have provided means for releasing the card holder, so that the same will be swung to open position for the insertion of a card therein. This means consists in a coin controlled apparatus which comprises an operating lever 21 disposed on the other face of the support, adjacent one side of the card holder, and which has its upper end mounted on a shaft 22 that extends through the support, and has on its outer end a lever 23. This lever 23 extends upwardly and is normally positioned adjacent one side of the coin chute 16. The lever 23 is held in inoperative position by means of a coil spring 24, which surrounds the shaft 22.

A coin slot 25 is formed through the support 1, and is disposed in alinement with the upper edge of the coin chute 16, when the locking plate 11 is in operative position. When it is desired to release the card holder, a coin of correct value is placed within the chute through the coin slot 25, and the same will drop down the chute until it is stopped at the lower end of the same by the coin stop 18. In this position the coin will be disposed within the notch 17 in the lower edge of the coin chute, and upon rocking the operating lever 21 against the tension of the spring 24, the lever 23 will be moved over and through the notch 17 in the lower edge of the coin chute. The coin will form a connection between the locking plate 11, and the operating mechanism, and consequently the locking plate will be moved against the tension of the coil spring 19. This plate will move a sufficient distance to release or withdraw the lugs 13 from the openings 8 in the extensions 5 of the card holder, and consequently the card holder will swing outwardly when so released under the tension of the coil springs 10. As soon as the coin within the coin chute is carried past the stop 18, the same will drop, and will be caught in a suitable discharge chute and carried to a receptacle. It will be observed that owing to the tension caused by the coil spring 19 as soon as the card holder is positioned back against the outer surface of the support, the locking lugs 13 will pass through the openings 8 in the sides of the holder, and the card will be securely held in locked position. This movement of the locking plate 11 will again aline the coin chute 16 and the slot 25, so that the device will be once more in operative position.

We have provided means for securely holding a card or other advertising matter

within the holder, which comprises a friction roller 26 which is journaled in bearings 27 between the sides 5 of the holder, and the inner surface of the support. The support 1 is provided with a slot 28, through which a portion of the friction roller will project out into the space between the support and the card holder. By this means when the card is inserted in the holder and the same is positioned against the outer surface of the support, the card will be securely held therein and will be prevented from dropping from the same. The lower edge of the card holder is provided with a slot 29, through which the card is adapted to be ejected but the friction roller will securely hold the card in the holder, and will prevent the same from dropping therefrom.

One end of the roller 26 has a short shaft 30 projecting therefrom as shown at 30, and the same extends through a slot 31 in the adjacent extension or wing 5 of the card holder. This slot 31 enables the card holder to swing freely backward and forward, toward and from the support without interfering or binding on the projecting portion of the roller. On the outer end of the extension 30 is mounted a small gear 32 which is provided with a spring pressed pawl 33 which prevents movement of the roller only in one direction. The outer face of the small gear 32 has teeth 34 thereon, which are adapted to mesh with a beveled gear 35 on a short shaft 36 projecting at right angles to the gear and rotatably mounted in a frame 37 secured to the inner face of the support. The inner end of the short shaft 36 terminates a short distance from the support 1, and an opening 38 is formed through the support in alignment with the end of the shaft.

The above described means form an operating mechanism for rotation of the frictional roller 26, so that the same may eject a card from the holder through slot 29 in the lower edge of the same. This mechanism is operated by a key being inserted through the opening 38 in the support, and engaging the short shaft 36. Upon rotation of this shaft by means of the key, the movement will be transmitted to the small gear 32, and hence to the friction roller. The spring pressed pawl 33 will prevent this gear from rotating in one direction, and hence it will be impossible to rotate the roller other than in the proper direction. The direction of movement of the roller will eject the card from the holder. This mechanism operated by a key is to prevent the card from being discharged by unauthorized persons.

This advertising device is designed for use primarily in hotels and other public places, where it is desired to display the personal card of a guest, etc., or for commercial or other purposes. When the card holder is

vacant, the same will be securely locked against the outer face of the support, and it will be impossible to swing it forward to insert a card therein until a coin has been inserted through the coin slot 25. Upon the insertion of a proper coin through this slot, the same will drop down through the chute 16 and upon movement of the lever 21, the coin will form a connection between the operating lever and the locking plate 11 in a manner hereinbefore described, and the card holder will be released so that it will automatically swing forward. A card is then inserted within the card holder, and the same is swung back to locked position, and will be automatically locked by the plate 11. After a certain length of time, when it is desired to remove the card from the holder, any authorized person, upon inserting a key through the opening 38 in the support, may engage the friction roller operating means, and upon rotation of this roller, the card will be ejected through the slot in the bottom of the card holder. This device is then once more in operative position, and the holder is ready to receive another card.

Owing to the fact that the friction roller 26 will only rotate in one direction, it will be impossible to insert an advertising card up through the slot in the bottom of the card holder, as the roller would be stationary, and it will be practically impossible to pass the card between the roller and the outer face of the holder. This will form a lock and will prevent unauthorized use of the advertising device. These advertising devices may be formed in any desired manner, and may be placed in a frame surrounded by advertising matter, or they may be disposed within a wall. Any desired type of coin discharge chute is used to carry the coins when they are dropped from the chute 16 to a receptacle, which will hold them until removal. The friction roller 26 is preferably covered with rubber, although any type of roller may be used. This roller is provided with short stub shafts at either end that are journaled in the bearings 27. These bearings are secured to the inner surface of the support by screws or in any other desired manner.

From the foregoing description, the construction of our improved device will be readily understood, and it will be seen that we have provided a simple and efficient means for carrying out the objects of this invention.

We claim:

1. A device of the class described comprising a support, a card holder movable toward and from said support having wings at its sides projecting through slots in the same, a locking plate slidably mounted on said support having notches in one edge through which the edges of said wings are adapted to move, lugs projecting into said notches

and adapted to pass through openings in said wings to lock the card holder against the support, spring means for normally holding the plate so as to retain the lugs in 5 locked position, and means for moving said plate against the tension of the spring means to release the wings.

2. A device of the class described comprising a support, a card holder movable toward and from said support and having its 10 sides projecting through slots in the same, a locking plate slidably mounted on said support and having notches in its lower edge, guide studs on the support extending 15 through said notches, a bracket adjacent one end of the plate, locking lugs and extending into the notches and adapted to pass through openings in said sides, a spring for normally holding the plate so as to retain the lugs in 20 locked position, and means for moving said plate against the tension of the spring to release the lugs and allow the holder to move outwardly.

3. A device of the class described comprising a support, a card holder hinged to the 25 same, said wings on said holder positioned through slots in the support and provided with stops to limit the outward movement of the same, spring means to exert a constant

outward tension on said holder, and means 30 to detachably lock the holder against the support.

4. A device of the class described comprising a support in the form of a plate having a pair of parallel slots formed therethrough, a card holding frame having a transparent front, said frame being pivoted to the front side of said support on a line extending between the slots thereof, a pair of wings projecting rearwardly from the 40 sides of the frame through said slots, said wings having stops to limit the forward movement of the frame and having openings, a locking plate slidably mounted on the rear face of the support and having 45 locking lugs to project through said openings, and means for shifting said plate to remove said lugs from said openings to permit forward movement of the wings.

In testimony whereof we have hereunto 50 set our hands in the presence of two subscribing witnesses.
